(57) **CLAIM**

The ornamental design for a diagnostic device, as shown and described.

DESCRIPTION

FIG. 1 is an exploded elevated perspective view of a diagnostic device, showing our new design.

FIG. 2 is an elevated perspective view of the diagnostic device of FIG. 1.

FIG. 3 is an exploded front elevation view of the diagnostic device of FIG. 1.

FIG. 4 is a front elevation view of the diagnostic device of FIG. 1.

FIG. 5 is an exploded right side elevation view of the diagnostic device of FIG. 1.

FIG. 6 is a right side elevation view of the diagnostic device of FIG. 1.

FIG. 7 is an exploded left side elevation view of the diagnostic device of FIG. 1.

FIG. 8 is a left side elevation view of the diagnostic device of FIG. 1.

FIG. 9 is an exploded rear elevation view of the diagnostic device of FIG. 1.

FIG. 10 is a rear elevation view thereof.

FIG. 11 is an exploded elevated rear perspective view of the diagnostic device of FIG. 1.

FIG. 12 is an elevated rear perspective view of the diagnostic device of FIG. 1.

FIG. 13 is an exploded top view of the diagnostic device of FIG. 1.

FIG. 14 is a top view of the diagnostic device of FIG. 1.

FIG. 15 is an exploded bottom view of the diagnostic device of FIG. 1.

FIG. 16 is a bottom view of the diagnostic device of FIG. 1; and,

FIG. 17 is an embodiment of a display that can be displayed on a screen of the above diagnostic device or on other medical devices.

The portions of the diagnostic device shown in broken lines form no part of the claimed design.

1 Claim, 9 Drawing Sheets
